UNITED STATES PATENT OFFICE.

HERBERT R. KEITHLEY, OF CHICAGO, ILLINOIS.

FREIGHT-CAR.

SPECIFICATION forming part of Letters Patent No. 740,142, dated September 29, 1903.

Application filed May 21, 1903; Serial No. 158,115. (No model.)

To all whom it may concern:

Be it known that I, HERBERT R. KEITHLEY, a citizen of the United States, residing at Chicago, in the county of Cook, in the State 5 of Illinois, have invented new and useful Improvements in Freight-Cars, of which the following is a specification.

This invention relates to a metal railway freight-car which is built up of ordinary 10 rolled shapes and plates, and more particularly to a combined gondola and hopper-bottom car.

The object of the invention is to produce a light strong car of simple construction 15 and composed of the minimum number of parts and weight of metal consistent with great rigidity and carrying strength.

The improvements are directed to certain features of construction which will appear 20 from the following description and claims.

In the accompanying drawings, consisting of four sheets, Figure 1 is a side elevation of one-half of a combined gondola and hopper-bottom car embodying the invention. Fig. 2 25 is a longitudinal vertical section of one-half of the car in line 2 2, Fig. 4. Fig. 3 is a bottom plan view of one-half thereof. Fig. 4 is a transverse vertical section thereof in line 4 4, Fig. 1. Fig. 5 is a transverse vertical section thereof in line 5 5, Fig. 1. Fig. 6 is a transverse vertical section thereof in line 6 6, Fig. 1. Fig. 7 is a fragmentary vertical central longitudinal section thereof in line 7 7, Fig. 3. Fig. 8 is a fragmentary trans- 30 verse section showing one of the bolsters.

Like letters of reference refer to like parts in the several figures.

Briefly stated, the car is composed of vertical sides in the form of built-up plate-girders which are supported by body-bolsters arranged in the usual relation and serve as the main carrying elements or members of the car, vertical ends which connect the sides, longitudinal center sills arranged in their 45 usual relation at the center of the car, transverse transoms, and floor-beams arranged between the bolsters, and a bottom which connects the sides and ends of the car is composed of horizontal bottom or floor plates 50 and hoppers arranged on opposite sides of the center sills between the bolsters and transoms. Each plate-girder side is composed of

vertical end web-plates A, a center web-plate A', a top or compression chord or member B, and a lower or tension chord or member C. 55 The center web-plate is arranged in vertical plane outside of the plane of the end web-plates, with its ends overlapping and riveted to the inner ends of the end web-plates. The upper chord preferably consists of an angle-bar having a vertical flange inside of and riveted to the upper edges of the web-plates and a horizontal flange projecting outward over the upper edges of the web-plates. The lower chord preferably consists of an angle-bar having a wide vertical flange arranged inside of and connected to the web-plates by a double row of rivets and a horizontal flange which projects inwardly from the lower edge of the vertical flange. 60 65 70

c represents a filler-plate inserted between the vertical flange of the upper chord and the center web-plate. Each side is provided with two substantially triangular vertical plates D, the upper edges of which are arranged 75 between the center web-plate and the lower chord to which they are connected by the rivets connecting the lower chord with the web-plate.

D' represents a vertical plate which extends from one triangular plate to the other, with its upper edge arranged between the center web-plate and lower chord, to which it is connected by the rivets connecting the chord and web-plate together. The plates D 80 and D', which extend below the lower chord, 85 constitute, respectively, the outer side walls of the hoppers and the supports for the ends of the transverse transoms.

d represents vertical stiffeners riveted to 90 the web-plate and vertical plates D D' of the plate-girder sides.

Each of the end walls of the car preferably comprises a vertical plate E, connected to the ends of the plate-girder sides by vertical 95 corner-posts e or in any other suitable manner, and an upper angle-bar e', arranged similarly to the upper chords of the plate-girder sides.

F represents the longitudinal center or 100 draft sills, which are located in their usual relation at the center of the car below the floor-line and preferably consist of ordinary channel-beams arranged with their webs ver-

tical and their flanges projecting horizontally outward.

The body-bolsters, which are arranged in their usual relation near the ends of the car, are preferably constructed as shown in Figs. 1, 2, and 8. Each bolster comprises a pair of separated vertical members *f* at each side of the center sills, secured in any suitable manner at their inner ends to the center sills and projecting outwardly therefrom beneath the horizontal flanges of the lower chords of the plate-girder sides to support the latter. The lower edges of the vertical members of the bolsters are connected by a continuous cover-plate *f'*, which extends from one end to the other of the bolster beneath the center sills. The bolster construction thus far described is set forth more in detail in my United States Letters Patent No. 725,849, dated April 21, 1903. The upper chord of the bolster is formed by the horizontal floor-plates of the car, as hereinafter described. Transverse transoms are arranged between the body-bolsters. Each transom is preferably in the form of a built-up plate-girder constructed as follows, (see Figs. 2 and 5:)

G represents vertical web-plates, which extend from the center sills to the vertical depending plates *D'* of the plate-girder sides, to which and the center sills the web-plates are connected by angle-plates or in any other preferred manner.

g represents angles extending from the center sills to the side plates *D'* and having their vertical flanges riveted to the upper edges of the web-plates of the transom.

g' is a plate extending from end to end of the transom over the center sills and riveted to the horizontal flanges of the angles *g*. This plate forms a continuous or unbroken upper chord for the transom.

g² *g³* represent, respectively, a flanged bar, preferably an angle-bar, and a plate which extends from end to end of the transom beneath the center sills, the angle-bar having its vertical flange riveted to the vertical web-plates of the transom and the plate *g³* being riveted to the horizontal flange of the angle *g²*. This angle and plate form a continuous lower chord for the transom. *g⁴* represents a short vertical channel-plate arranged between the center sills and having its vertical flanges riveted to the center sills and its lower end riveted to the angle *g²* of the lower chord of the transom.

H represents floor-beams, which are arranged between the body-bolsters and transoms nearer to the bolsters and extend from the center sills to the sides of the car. The floor-beams are preferably formed of *Z*-bars and are connected at their inner ends to the center sills by angle-plates or in any other suitable manner. The outer ends of the floor-beams are secured in any suitable manner to the depending lower ends of vertical angle-bars *h*, which constitute stiffeners for the plate-girder sides. The bottom or floor

at each end of the car is formed by horizontal end and intermediate floor-plates *I* and *J*. The end plate *I* is secured at its outer end to the adjacent end of the car by an angle-bar *i* or in any other suitable manner and extends over the vertical members of the bolster. The intermediate floor-plate *J* extends from over the bolster to a point over the adjacent floor-beam *H*. The meeting ends of the floor-plates overlap over the bolster, as clearly shown in Fig. 2, and are riveted together and to the upper flanges of the vertical members of the bolster, the plates thus forming an upper or tension chord for the bolster of double thickness and which extends continuously or unbroken from end to end of the bolster. The side edges of the floor-plates *I* and *J* extend beneath and are riveted to the longitudinal tension-flanges of the plate-girder sides, suitable filler-plates *j* being inserted between the said flanges and the plate *I*. Both of the floor-plates *I* and *J* are riveted to the upper flanges of the center sills. The central horizontal portion of the bottom or floor is formed by a plate *K*, which extends from one transom to the other and overlies and is riveted to the upper flanges of the transoms. The side edges of the plate underlie and are riveted to the horizontal tension-flanges of the plate-girder sides.

L represents a horizontal cover or connecting plate for the center sills. It rests on and is riveted to the top flanges of the center sills, extending from bolster to bolster and projecting laterally beyond or overhanging the flanges of the center sills. This cover-plate is located beneath the central and intermediate floor-plates *J* and *K*.

The hoppers or hopper portions of the bottom, of which there are four, are arranged between the transoms and floor-beams *H* on opposite sides of the center sills. The outer side wall of each hopper is formed by one of the depending triangular plates *D* of the sides, and the inner side wall is formed by a correspondingly-shaped plate *M*, arranged vertically beside the adjacent center sill. The plate *M* is connected at its upper edge to the overhanging portion of the cover-plate *L* for the center sills by an angle *m* or otherwise. The inclined bottom of the hopper is formed by a plate *m'*, secured at its side edges to the side walls *D* and *M* of the hopper. The upper transverse edge of the inclined hopper-plate *m'* extends between and is riveted to the adjacent floor-beam and end of the intermediate floor-plate *J*. The other transverse wall of the hopper is formed by a door *N* and the inclined plate *n*, to which the door is hinged. The hinge-plate *n* is connected at its side edges to the side walls of the hopper, and its upper edge extends between and is riveted to the angle and plate forming the upper chord of the adjacent transom. The hopper-door swings downwardly toward the center of the car in opening.

The end sills of the car are preferably con-

structed as shown in Figs. 2 and 3. Each end sill consists of a Z-bar O, arranged with its web horizontal, its outer flange projecting downwardly and its inner flange projecting upwardly beside the lower portion of the end wall-plate of the car, to which said flange is riveted. The end portions of the horizontal flanges of the angles forming the tension-chords of the plate-girder sides project outwardly beyond the end wall-plates of the car beneath the web of the end sill, to which they are riveted or bolted, thus rigidly connecting the ends of the end sill with the ends of the tension-chords of the plate-girder sides.

15 The door-operating mechanism is preferably constructed as follows: The two doors for the adjacent hoppers on opposite sides of the center sills are connected by a common flanged bar P, preferably a channel-bar riveted to the lower free ends of the doors. This connecting-bar is connected centrally by a link p to a crank p', located between the center sills and secured to a transverse rock-shaft p², which is journaled in suitable bearings p³, secured to the center sills and the inclined bottom plate of one of the hoppers. The shaft is provided at its outer end with a rock-arm p⁴. Q represents a door-operating lever which is pivoted on a stud or pin q, secured to the side plate D adjacent to the rock-arm p⁴. The lever is provided with a cam plate or portion q', the circular face of which in the position of the lever shown by full lines in Fig. 1 engages the rock-arm p⁴ to hold the latter and the rock-shaft stationary with the doors closed. To open the doors, the lever q is swung upwardly, as shown by dotted lines in Fig. 1, which releases the rock-arm p⁴ and permits the doors to swing open. In the open position of the doors the rock-arm engages the inclined face of the cam, and when the lever is swung downwardly the rock-arm and the rock-shaft are returned to the full-line position shown in Fig. 1, thereby closing the doors and locking the same. The lever Q thus affords a convenient and desirable operating means as well as the locking device for the doors.

I claim as my invention—

50 1. In a car, the combination of one or more vertical bolster members, and horizontal floor-plates the meeting ends of which overlap each other over said vertical bolster members and are riveted together and to said vertical bolster members to constitute the upper chord of the bolster, substantially as set forth.

2. In a car, the combination of one or more vertical bolster members, two horizontal floor-plates the meeting ends of which overlap each other over said vertical bolster members and are riveted together and to said vertical bolster members to constitute the upper chord of said bolster, and a compression-chord connected to said vertical bolster member, substantially as set forth.

65 3. In a car, the combination of parallel vertical bolster members, and horizontal floor-

plates the meeting ends of which overlap each other over said vertical bolster members, and are riveted together and to said vertical bolster members to constitute the upper chord of the bolster, substantially as set forth.

4. In a car, the combination of one or more bolster members, center sills, and floor-plates the meeting ends of which overlap each other and are connected to the bolster members to constitute the upper chord of the bolster, one of said floor-plates forming a cover-plate for a portion of the center sills, substantially as set forth.

15 5. In a car, the combination of one or more vertical bolster members, center sills, two horizontal floor-plates the meeting ends of which overlap each other over the vertical bolster members and are connected to said vertical bolster members to constitute the tension-chord of the bolster, one of said floor-plates forming a cover-plate for a portion of the center sills, and a compression-chord secured to said vertical bolster members, substantially as set forth.

6. In a railway-car, the combination of one or more bolster members, center sills, two horizontal floor-plates the meeting ends of which overlap each other and are secured to the bolster members to constitute the upper chord of the bolster, one of said floor-plates forming a cover-plate for a portion of said center sills, and a longitudinal cover-plate for said center-sills riveted to the other of said floor-plates and to said center sills, substantially as set forth.

7. In a railway-car, the combination of one or more bolster members, two horizontal floor-plates, the meeting ends of which overlap each other over and are secured to said bolster members to constitute the upper chord of the bolster, and a hopper, one of said floor-plates extending to one end of the car and said other floor-plate extending to said hopper, substantially as set forth.

8. In a car, the combination of a bolster, center sills, hoppers arranged on opposite sides of said center sills, two horizontal floor-plates, the meeting ends of which are connected together and to said bolster, one of said floor-plates extending to one end of the car, and the other floor-plate extending to the adjacent end of the hoppers, substantially as set forth.

9. In a car, the combination of a bolster, a transom, a floor-beam arranged between said bolster and said transom, center sills, hoppers arranged on opposite sides of said center sills between said transom and floor-beam and secured to the latter, and horizontal floor-plates, one of which extends from said bolster to the end of the car and the other of which extends from said bolster to said floor-beam, the meeting ends of said floor-plates being connected to each other and to said bolster, substantially as set forth.

10. In a car, the combination of a plate-girder side comprising web-plates having

their meeting ends lapped and riveted together, a tension-chord secured to the lower edges of said web-plates, a hopper side plate interposed between said tension-chord and a 5 web-plate of said plate-girder side and extending below said tension-chord, and a plate interposed between said tension-chord and a web-plate of said plate-girder side and extending below said tension-chord to form a 10 support for the car-transom, substantially as set forth.

11. In a car, the combination of side girders, center sills, a built-up plate-girder transom comprising web-plates arranged on opposite sides of said center sills and extending from said center sills to said side girders, a continuous upper chord extending over said center sills and connected to said web-plates, and a lower chord comprising an angle-bar 20 extending continuously from side to side beneath said center sills and having an upwardly-extending vertical flange secured to said web-plates, and a reinforcing-plate secured to the horizontal flange of said angle-bar, substantially as set forth.

12. In a car, the combination of plate-girder sides having tension-chords, an end wall, an end sill consisting of a Z-bar arranged with

its web horizontal and one flange vertical and secured to said end wall of the car, the end 30 portions of the tension-chords of the plate-girder sides projecting beyond said end wall beneath the horizontal web of said end sill to support the latter, substantially as set forth.

13. The combination of a hopper and its 35 door, of means connected to said door, and a door-operating lever provided with a cam having a substantially radial face which engages said means to move the door and with a curved face which engages said means to lock the 40 door in closed position, substantially as set forth.

14. The combination with a hopper and its door, of a rock-shaft connected to said door and provided with a rock-arm, a door-operating lever provided with a cam having a portion which engages said rock-arm to operate the door and a portion which engages said rock-arm to lock the door in closed position, 45 substantially as set forth.

Witness my hand this 18th day of May, 1903.
